To all whom it may concern:

The accompanying photographic illustration fully represents my new invention.

This invention relates to a new design for a carpet, and more particularly to two new center figures for the same, one of octagonal, the other of more irregular form. The octagonal figure has semicircular protuberances on every alternate side, and contains a floral scroll

within the middle. The other large figure has four forked straight-sided projections, and between them also rounded protuberances, and is otherwise decorated and provided with lines and scrolls, as shown.

I claim as my invention—
